UNITED STATES PATENT OFFICE.

GEORGE JAMES THOMAS, OF NEW YORK, N. Y

DESIGN FOR A DOMINO.

No. 38,868.

Specification for Design.

Patented Nov. 5, 1907.

Application filed July 22, 1907. Serial No. 385,096. Term of patent 14 years.

To all whom it may concern:

Be it known that I, GEORGE JAMES THOMAS, a subject of Great Britain, residing at New York, in the county of New York and State of New York, have invented a certain new and original and ornamental Design for Dominos.

This invention relates to a new and original design for dominos, of which the following is a specification, reference being had to the accompanying drawing forming a part of the application.

The figure of the drawing shows a domino embodying the design which is of the shape of a waving flag, having stripes and stars upon the face thereof.

I claim:—

The ornamental design for a domino, as shown.

GEORGE JAMES THOMAS.
